UNITED STATES PATENT OFFICE

RAY R. HUTCHESON, OF RICHMOND HILL, NEW YORK, ASSIGNOR TO WM. DEMUTH
& CO., A CORPORATION OF NEW YORK

DESIGN FOR A BOTTLE STOPPER

Application filed September 23, 1930. Serial No. 37,054. Term of patent 3½ years.

To all whom it may concern:

Be it known that I, RAY R. HUTCHESON, a citizen of the United States of America, and a resident of Richmond Hill, county of Queens, and State of New York, have invented a new, original, and ornamental Design for Bottle Stoppers, of which the following is a specification, reference being had to the accompanying drawing, forming a part hereof.

The dominating feature of the design resides in the representation of a golf ball surmounting the cork of the bottle stopper and carrying a flag or pennant.

I claim:

The ornamental design for a bottle stopper substantially as shown and described.

RAY R. HUTCHESON.
